UNITED STATES PATENT OFFICE.

CHARLES F. McGLASHAN, OF SANTA BARBARA, CALIFORNIA.

RAILWAY-BALLOON AND ELECTRIC TRAMWAY AND TRUCK.

SPECIFICATION forming part of Letters Patent No. 247,571, dated September 27, 1881.

Application filed June 24, 1881. (No model.)

To all whom it may concern:

Be it known that I, CHARLES F. McGLASHAN, of the city and county of Santa Barbara, State of California, have invented an Improved Rail- 5 way-Balloon and Electric Tramway and Truck; and I hereby declare the following to be a full, clear, and exact description thereof.

My invention relates to a new tramway and truck, and, in connection therewith, it relates 10 to certain modifications thereof, whereby results are produced which are all dependent upon the main invention.

It consists in supporting wires, ropes, rods, or rails above the ground by means of posts 15 in such a manner that a peculiar truck may travel on said wire, &c., with safety.

This traveling truck may be made to support a car and act as running-gear for it, or it may be utilized as a guide for a balloon. It 20 may further be used as a means for connecting an electric circuit, whereby communication may be held with the car of a balloon or with a moving train.

The main feature is the tramway with its 25 peculiar traveling truck; but slight modifications are necessary in both to accomplish the results stated. The means for accomplishing the above will be fully set forth in the course of the following description and by reference 30 to the accompanying drawings, in which—

Figure 1 shows the tramway and truck. Fig. 2 shows its application to a car. Fig. 3 is a modification of its application to a car. Fig. 4 shows enlarged view of truck. Fig. 5 shows 35 application of tramway and truck to a balloon. Fig. 6 shows its further application to a car.

In Fig. 1, let A represent a series of posts or supports covering any desired distance. From the tops of the posts extend top pieces, 40 B. They project inwardly horizontally and turn under and backward, forming a socket which receives the wires C C. They are carried down and secured to the posts. These form supports and braces for the wires and hold them out away from the posts. In fitting over the wires C C they are made to cover them smoothly, so as to present no obstruction to the passing wheels.

Let D in Fig. 4 represent my truck. It is 45 composed of two side standards, E E, having vertical slots m, in which are journaled groove-

faced wheels F. On each side one wheel is above the other. The outer walls of the standards are severed, as shown at r, and a space left between the upper periphery of one wheel and the lower periphery of the wheel above. The severed ends of the walls of the standards are rounded off, as shown. The two standards are connected by means of the bent arms G, which are secured to a block, H, at their centers. These arms may, however, be bolted together without the intervention of the block H, except for certain purposes hereinafter shown.

This truck is fitted upon the wires C C, Fig. 65 1, said wires passing between the wheels F, within their grooved faces, and the open walls of the standards toward the outside. The truck can then travel along the wires, the inside walls of the standards finding no obstruction, and the outside severed walls passing by the supports or braces B without interference.

The necessity and advantage of this construction is this: By having a double-wheeled truck, one wheel above the other, it cannot 70 leave the track, and it always presents a rolling surface to the track. No upward strain can cause it to rise, nor can a side strain cause it to tip over; but in order to have this kind of a truck the track-wires must be suspended 75 from supports in some manner which will take them away from the posts. This is done by the horizontal supports B; and to pass these supports the outer walls of the standards are provided with openings which will allow the 80 truck to pass the supports, and, being rounded, will protect the wheels, and at the same time permit the natural play of the truck when passing them.

Utilizing this tramway and truck, I have 90 shown in Fig. 2 how it can be applied to a car. I can have any suitable number of wheels in each truck. I deem it preferable to have eight in each. The cars cannot jump the track, and thus the danger attending elevated 95 railways is obviated.

In Letters Patent No. 152,145, dated June 16, 1874, issued to me, I show a means for guiding balloons. As an improvement upon the means there shown, I have shown in Fig. 5 the application of this tramway and truck to this purpose.

Let I represent the balloon, having a car, J,

in which is a windlass, K, which winds up a rope, L, connecting the car of the balloon with the truck D traveling upon the tramway. The rope L is connected with the central block, H, of the traveling truck. In order to properly guide and direct the rope L, I have the circular band M, Figs. 4 and 5, attached to the standards of the truck, and the inclined semi-circular bands N N attached to the top of the standards, and having their ends secured to the band M. When the balloon shifts from side to side the rope will be prevented by the bands N N from meeting with the sharp corners of the standards.

15 The same effectiveness which characterizes this truck as a car-truck makes it useful as a traveler for a balloon. It runs smoothly and cannot leave the track. By having four wheels, as here shown, it serves as a check upon the balloon when it goes too far to one side, because in straining over it binds or cramps the wheels against the wires.

In the application of this tramway to balloons it is obvious that I may modify both tramway and truck, and yet not change the principle of the invention, by having only one suspended wire or track and only one standard containing two wheels. This would reduce the friction and be more economical in construction.

30 The tramway and truck here shown, while serving as a means for guiding balloons, will further serve the purpose of acting as a conductor to hold telegraphic communication with the balloon. To accomplish this the wires or rails C C must be insulated. This can be done, as shown in Fig. 5, where the supports B are covered with appropriate material, such as gutta-percha.

40 The wires C must, of course, be separately insulated, the connection with one being through a wire, a, and the connection with the other through a wire, b, at the other end.

The central block, H, of the truck must be 45 of some non-conducting substance, so that the two parts of the truck are kept separate and the circuit preserved. Wires e are attached to the bent connecting-links G, and thence pass up, either within the rope L or beside it, to 50 the car of the balloon, and are there attached to a proper instrument. The wires e are insulated suitably. A circuit is thus made through one of the wires or rails C and the rolling wheels of the truck, up one wire e to 55 the balloon, and down again through the other wire e to the other side of the truck, and thence through the wheels on that side and rail or wire C to the other end. This will be found practicable, because the wheels of the 60 truck are always in contact with the wires or rails. If the upper wheels are raised, the lower ones touch, and vice versa. If, however, this were not true, and the circuit were interrupted by the swift motion of the truck, causing the 65 wheels to leave the rail for an instant, I can attach a metal follower to the truck, which

would rest upon the rails all the time. This same principle can be further carried out in its application to a moving car. In Fig. 6 I show this. Upon the ground, between the 70 posts A of the tramway, are the ordinary rails, P, of a railway-track. Q represents a car upon them. From the top of the car a rope, R, extends to the central block, H, of the truck D above. The truck is thus carried along with 75 the car. The wires e, attached to different sides of the truck, pass down through the top of the car to the instrument within the car. The electric circuit is thus made, so that telegraphic communication can be held with the 80 moving train, as with the balloon.

If I should find that the distance between the two lines of posts A is too great to support the wires C C in proper position over the train without making the supports B too long, 85 I could adopt the construction shown in Fig. 3. Here I place beams S across the posts A and suspend pieces T therefrom the proper width. Extending horizontally from these pendent rods are the supports B, which sustain the 90 wires C C, as before. It will be seen from this description that the main feature of my invention is the elevated tramway, constructed as shown, and the peculiar truck, whereby it is enabled to pass the supports and yet have superposed running wheels, making it a practical safety-truck.

Having this traveling truck and tramway, I am enabled with but the merest modifications to apply it to the various uses herein specified.

Having thus described my invention, what I claim as new, and desire to secure by Letters Patent, is—

1. The tramway consisting of the lines of posts A, having horizontal inwardly-extending 105 supports B, sustaining parallel horizontal wires or tracks C C, combined with the traveling truck D, consisting of the slotted standards E E, carrying rollers or wheels F, with grooved faces adapted to travel upon and under the 110 wires C C, said standards having their outer walls or sides severed to form an opening opposite the under periphery of the upper wheels and the upper periphery of the lower wheels, and joined together by the arms G, substantially as and for the purpose herein described.

2. The elevated tramway, consisting of the lines of posts A, having horizontal supports B, carrying horizontal parallel wires or tracks C C, and the truck D, with its side openings, and having rollers or wheels F, adapted to travel upon and under the wires C C, in combination with a car or its equivalent, substantially as and for the purpose herein described.

3. The improvement in elevated railways, consisting in supporting horizontal parallel tracks by means of horizontal supports extending from vertical posts, and providing a car having trucks the wheels in which are adapted to travel upon and under the rails and to pass 130 the horizontal supports by means of openings or slits in the outer sides of the trucks, sub-

stantially as and for the purpose herein described.

4. In combination with an elevated tramway consisting of posts A, horizontal supports B, 5 and parallel wires or tracks C C, and the traveling truck D, with its slotted standards E E, having open outer sides and rollers or wheels F, the balloon attached to and guided by the traveling truck D by means of the rope L, substantially as and for the purpose herein described.

5. The means for establishing telegraphic communication with a balloon or railway-car in motion, consisting of the battery-wires a and 15 b, insulated elevated tramway wires or rails C C, traveling truck D, with its central insulating block, H, and insulated wires e e, connecting the traveling truck with the balloon

or moving car, substantially as herein described.

6. The improvement in telegraphy—namely, in establishing telegraphic communication with a balloon—consisting in attaching said balloon to a traveler moving upon a tramway, the rails or wires of which are insulated and connected with appropriate batteries, and completing the electric circuit through said traveler by means of wires connected therewith and with the balloon, substantially as herein described.

In witness whereof I have hereunto set my 30 hand.

CHARLES F. McGLASHAN.
